DESIGN FOR A DAIRY PRODUCTS INDICATOR

Caroline L. Sentney, Indianapolis, Ind.

Application July 24, 1939, Serial No. 86,203

Term of patent 3½ years

To all whom it may concern:

Be it known that I, Caroline L. Sentney, a citizen of the United States and a resident of Indianapolis, county of Marion, and State of Indiana, have invented a new, original, and ornamental Design for a Dairy Products Indicator, of which the following is a specification, reference being had to the accompanying drawing, forming part thereof.

In the drawing, Fig. 1 is a front elevational view of the dairy products indicator showing my design and Fig. 2 is a rear elevational view thereof.

I claim:

The ornamental design for a dairy products indicator, as shown.

CAROLINE L. SENTNEY.
